ATTORNEYS. .

UNITED STATES PATENT OFFICE.

JOHN A. ANIELLO, OF NEW ORLEANS, LOUISIANA, ASSIGNOR TO JOSEPH O. THEARD, OF SAME PLACE.

ADVERTISING MEDIUM.

SPECIFICATION forming part of Letters Patent No. 625,530, dated May 23, 1899.

Application filed December 27, 1897. Serial No. 663,649. (No model.)

To all whom it may concern:

Be it known that I, JOHN A. ANIELLO, of New Orleans, in the parish of Orleans and State of Louisiana, have invented a new and 5 Improved Advertising Medium, of which the following is a full, clear, and exact description.

The object of the invention is to provide a new and improved advertising medium in the 10 form of a vehicle arranged to attract great attention while being drawn through the streets, over roads, or other highways.

The invention consists of novel features and parts and combinations of the same, as 15 will be fully described hereinafter and pointed out in the claims.

Reference is to be had to the accompanying drawings, forming a part of this specification, in which similar characters of reference indicate corresponding parts in both the figures.

Figure 1 is a sectional side elevation of the improvement, and Fig. 2 is a cross-section of the same.

A vehicle is provided with a wagon-body A, 25 mounted on front wheels B and rear wheels C, of which the latter are secured on an axle C', carrying a pulley C², connected by a belt C³ with a pulley C⁴, secured on a longitudinally-extending shaft D, journaled in suitable 30 bearings in the bottom of the wagon-body A, as is plainly indicated in the drawings, the belt C³ extending through an opening in the bottom of the said wagon-body.

When the vehicle is drawn forward, the 35 wheels C in rotating the axle C' also rotate the pulleys C², which by the belt C³ and the pulleys C⁴ rotate the shaft D, the latter serving to impart a traveling motion to endless bands F F', arranged in window-openings A' 40 A² formed in the sides of the vehicle-body A. The rotary motion of the shaft D is also used for actuating an organ located within the said vehicle-body, and the shaft is further used for actuating a trap-door H, carrying a figure 45 I, carrying bells and arranged to appear and disappear in an opening A³, arranged in front of the wagon-body.

As shown in the drawings, a number of advertising-bands F F' are used on each side of 50 the wagon-body, and the bands F are mounted on rollers F² and F³, journaled in suitable

bearings in the wagon-body. Similar rollers F⁴ and F⁵ are used for the bands F' on the other side of the wagon-body.

In order to impart a traveling motion to the 55 bands F F' while the vehicle is traveling along, I provide the following mechanism: On the shaft D, preferably near one end thereof, is secured a sprocket-wheel J, connected by a sprocket-chain J' with a sprocket-wheel J² on the roller F², and on this roller is arranged a sprocket-wheel J³, connected by a transverse sprocket-chain J⁴ with a sprocket-wheel J⁵, attached to the upper roller F⁴. When the shaft D is rotated, rotary motion 60 is transmitted by the means described to the upper rollers F² F⁴ to impart a traveling motion to the bands F F'. Thus the advertisements arranged on the bands F F' appear and disappear in the openings A' A² and can be 65 read by the persons attracted to the wagon.

In order to actuate the organ G, I provide the shaft D with a pulley K, over which passes a belt K', also passing over a pulley K², secured on the crank-shaft G' of an ordinary 70 organ G.

A platform H is hinged at H' to the front of the vehicle-body and is adapted to rest normally on cleats H², fixed to the wagon-body.

In order to impart a swinging motion to the platform H and the figure I, carried thereby, I provide the shaft D with a pulley L, over which passes a belt L', also passing over a pulley L², secured on a transverse shaft L³, 85 journaled in suitable bearings arranged within the vehicle-body. On the shaft L³ is attached an arm L⁴, adapted to engage the free end of the platform H, so as to swing the same upward to tilt the figure I into and partly out 90 of the opening A³ in the front of the vehicle-body, so that the figure is clearly visible by persons in the street, special attention being attracted by the figure and the sounding of the bells carried by said figure. When the 95 arm L⁴ leaves the free end of the platform H, then the latter swings down gradually to its resting position on the cleats H², the platform and figure being counterbalanced by a rope H², passing over a pulley H³ and carrying a 100 weight H⁴.

It is evident that when the device is dragged

along in the street motion is given to the endless advertising - bands F F'. At the same time music is produced within the vehicle-body to attract attention, and in addition the figure I appears periodically in the opening and the bells ring to further attract attention to the advertising medium.

Having thus fully described my invention, I claim as new and desire to secure by Letters Patent—

1. An advertising medium comprising a wheeled vehicle, a shaft mounted to turn in the vehicle-body and arranged to be driven by the movement of the vehicle, advertising bands mounted to travel and moved from the said shaft, a platform carrying a figure appearing through an opening in the vehicle-body, the said platform being mounted to swing, and means actuated from the shaft for imparting a swinging motion to the said platform, substantially as shown and described.

2. In an advertising medium, a wheeled vehicle provided with a body, a shaft mounted to turn in the vehicle-body and arranged to be driven by the movement of the vehicle, a shaft adapted when turned to operate a mu-

sical instrument located within the vehicle-body, the said shafts being each provided with a pulley and a belt passing over the said pulleys, substantially as set forth.

3. In an advertising medium, a wheeled vehicle provided with a body, a platform arranged within the vehicle-body and hinged thereto and normally resting on a support fixed to the wagon-body, the said platform carrying a figure appearing through an opening in the vehicle-body, a shaft journaled in the vehicle-body adjacent to the free end of the platform and provided with an arm adapted to engage the free end of the platform so as to swing the same upward, a shaft arranged to be driven by the movement of the vehicle, a driving connection between the said shafts, and a rope connected with the platform and passing over a pulley, the said rope carrying a weight for counterbalancing the platform and figure, substantially as described.

JOHN A. ANIELLO.
